UNITED STATES PATENT OFFICE.

JOHN D. ROGERS, OF PRINCETON, WEST VIRGINIA, ASSIGNOR OF ONE-HALF TO H. C. ELLETT, OF PRINCETON, WEST VIRGINIA.

FIRE-BRICK ARCH.

1,178,752.

Specification of Letters Patent. Patented Apr. 11, 1916.

Application filed September 24, 1913. Serial No. 791,615.

To all whom it may concern:

Be it known that I, JOHN D. ROGERS, a citizen of the United States, residing at Princeton, in the county of Mercer and State 5 of West Virginia, have invented certain new and useful Improvements in Fire-Brick Arches, of which the following is a specification.

This invention relates to fire brick arches 10 for boiler furnaces and has as its object to improve generally the construction of fire brick arches such as are employed for the purpose of providing a combustion chamber located between the grate and the flues of 15 the furnace. In the present practice such arches are supported or braced by means of heavy cast iron brackets to which the bricks comprising the arch are bolted. The employment of these brackets, however, presents 20 numerous disadvantages. They are of necessity massive and expensive to install and the bolts which secure the bricks to the brackets soon burn out, allowing the bricks to fall into the fire and in time the brackets 25 themselves become burned out and parts will fall into the combustion chamber thereby choking the cleaning holes.

The present invention therefore aims to 30 provide a fire brick arch which may be constructed from fire brick as now manufactured and placed upon the market without alteration and without the employment of brackets or bolts and without in any way obstructing or rendering less efficient the air 35 passages through the arch.

Another aim of the invention is to so construct the arch that the passage of air through the air passages may be regulated by a damper in accordance with the kind and 40 quality of fuel being burned in the furnace, also according to the color of the fire.

In the accompanying drawings: Figure 1 is a rear elevation, parts being shown in section, of the fire brick arch embodying the 45 present invention; Fig. 2 is a vertical sectional view on the line 2—2 of Fig. 1.

The arch is supported by means of a transverse bearer 1 which is preferably of cast steel and which, of course, extends 50 across the fire box between the grate and the flues as clearly shown in Fig. 1 of the drawings. The fire bricks comprising the arch proper are indicated by the numeral 2 and these bricks are of ordinary construction 55 and are arranged in superposed relation as

shown in the drawings, and each of the bricks is formed at suitable intervals with vertically extending openings 3, the openings being adapted to register when the bricks are properly arranged, so as to form 60 passageways extending vertically in parallel relation in the arch. The arch is capped by means of cap bricks 4 and that one of the fire bricks which is located below the cap bricks and which is indicated specifically by 65 the numeral 3^a, is formed with a series of openings 5 communicating with the under and rear faces of the brick, said openings, at their ends terminating at the under face of the brick, registering with the openings 3 and the said openings being flared in the direction of their ends which open at the back face of the brick.

As before stated, the bricks comprising 70 the arch are, in the present construction of such arches, braced by means of cast iron brackets to which the bricks are secured by means of bolts, but in view of the disadvantages of such a construction it is proposed by the present invention to fit within 75 the passageways in the arch, pipes 6 which serve to hold the bricks against relative displacement, thereby rendering unnecessary the employment of the brackets and bolts mentioned. The pipe 6 projects at its upper 80 end into that end of the respective opening 5 which is presented at the under side of the brick 3^a and at its lower end projects a sufficient distance downwardly into openings 85 7 formed in the cast steel bearer 1, the pipes 90 being in this manner securely anchored in the bearer. The openings 7 extend vertically in the bearer and fitted into the lower end of each opening is the neck 8 of a funnel 9, these funnels constituting intakes for the air 95 passages through the pipes 6 and openings 5, whereby upon forward movement of the locomotive, in the fire box of which the arch is arranged, air will be supplied to the fire box of the furnace for the purpose of securing 100 a more complete combustion of the fuel.

In order that the passage of air to the pipes 6 may be regulated, a damper 10 is arranged within the neck 8 of each of the funnels and the stems of the dampers are 105 provided each with a short arm 11, all of the arms being connected by a rod 12 adapted to be rocked, by any suitable operating means (not shown), for the purpose of moving the dampers.

From the foregoing description of the invention it will be seen that an arch constructed in accordance with the principles thereof will be substantial and will be devoid of metallic supports exposed to the action of the fire and which would be liable to burn out and clog the grate or clean-out openings of the combustion chamber. It will be understood of course that the damper 10 may be of the turning, sliding, or in fact any type.

The most important feature of the application of damper, is the opportunity to close this secondary air supply when "blowing up" an engine not in motion. It is then that all the draft should be through the fire, as the draft is not sufficient to properly mix the gases and this additional air only, tends to cool the fire box.

Having thus described my invention, what is claimed as new is:

1. In a locomotive boiler, a metal bearer disposed at the front of the fire box and formed with a plurality of vertical openings, a plurality of vertical straight metal pipes having their lower ends fitted in the vertical openings of the bearer, a plurality of heat resisting members slipped upon the vertical pipes to hold them in fixed relative position and fill the spaces between them to form a bridge wall, said members being supported upon the bearer and a plurality of dampers for controlling the admission of air through the vertical openings of the bearer and the vertical pipes, said dampers being connected for simultaneous operation.

2. In a locomotive boiler furnace, a metal bearer located near the front of the fire box at the bottom thereof and having a plurality of vertical openings, a plurality of vertically disposed straight metal pipes having their lower ends secured in the vertical openings of the bearer and in communication with said openings, a plurality of heat resisting members slipped upon the vertical pipes and closing the spaces formed between them to form a bridge wall at the front of the fire box and between the sides thereof, the upper ends of the pipes projecting a short distance above the members.

slipped thereon, and other heat resisting members surmounting the beforementioned members and formed with elbow shaped openings which flare at their delivery ends and have their opposite ends vertically disposed and receiving the upper projecting ends of the pipes. 55

3. In a locomotive boiler furnace, a metal bearer near the front of the fire box at the bottom thereof and having a plurality of vertical openings which are enlarged at their upper and lower ends, a plurality of vertically disposed straight metal pipes having their lower ends secured in the upper enlarged ends of the vertical openings of the bearer and in communication with such vertical openings, a plurality of heat resisting members slipped upon the vertical pipes and closing the spaces formed between them to form a bridge wall at the front of the fire box and between the sides thereof, the upper ends of the pipes projecting a short distance above the members slipped thereon, other heat resisting members surmounting the before mentioned members and formed with elbow shaped openings which flare at their delivery ends and have their opposite ends vertically disposed and receiving the upper projecting ends of the pipes, and necked funnels arranged below the bearer, with their necks fitted in the lower enlarged ends of the vertical openings of the bearer. 75

4. In a locomotive boiler firebox, a transverse refractory wall arranged at the forward end thereof and spaced from the flue sheet, a bridge member spanning the firebox and supporting the wall, said wall being provided with vertically extending passages, hollow metallic wall supports secured at their lower ends to said bridge member, extending upwardly in said passages, retaining the wall in position and adapted to admit air to the firebox. 85 90

In testimony whereof I affix my signature in presence of two witnesses.

JOHN D. ROGERS. [L.S.]
